UNITED STATES PATENT OFFICE.

CHARLES A. JUENGST, OF CROTON FALLS, NEW YORK.

INTERNAL-COMBUSTION ENGINE.

1,244,862.

Specification of Letters Patent. Patented Oct. 30, 1917.

Application filed March 13, 1915. Serial No. 14,063.

To all whom it may concern:

Be it known that I, CHARLES A. JUENGST, a citizen of the United States, and a resident of Croton Falls, in the county of Westchester and State of New York, have invented certain new and useful Improvements in Internal-Combustion Engines, of which the following is a specification.

The present invention relates generally to internal combustion engines, and has more particularly reference to two-cycle engines.

In a companion application Serial No. 14,962, filed March 13, 1915, I have disclosed and claimed a two-cycle engine in which there is provided means for introducing fuel substantially at the end of the power stroke of the piston into one end of the combustion chamber at a point adjacent to the ignition means under sufficient compression and in a constantly widening stream from its point of admission, which stream by its expansion displaces the products of combustion *en masse* and insures its own localization adjacent to the ignition means on the compression stroke of the piston.

The present invention is an improvement on the invention disclosed in said companion application and has for its main object the prevention of the mingling of the oil splash with the incoming fuel.

Other objects of the invention will appear as the specification proceeds.

In accordance with the above the invention comprises a two-cycle engine consisting of a cylinder provided with a crank case and a hollow piston, said elements forming a combustion chamber and a crank case compression chamber, said hollow piston communicating at all times with the crank case and at suitable intervals with the combustion chamber, together with means for feeding fuel directly into said piston but in such a way that the incoming fuel is shielded from the oil splash in the crank case.

Other features of construction, combination of parts and arrangement of elements will appear as the specification proceeds.

In the accompanying drawings the invention is disclosed in a concrete and preferred form but changes of construction may be made without departing from the legitimate and intended scope of the invention as expressed in the appended claims.

In the drawings:

Figure 1 is a vertical sectional view of a

two-cycle engine embodying the invention, with the piston shown at the end of the compression stroke.

Fig. 2 is a view similar to Fig. 1, with the piston shown at the end of the power stroke. 60

Fig. 3 is a horizontal sectional view on the line 3—3 of Fig. 1.

Fig. 4 is a horizontal sectional view on the line 4—4 of Fig. 1.

Similar characters of reference indicate 65 corresponding parts in the different views.

1 indicates the cylinder of the engine provided with a main portion 2 and a supplemental hollow extension 3, there being a tapered portion 4 which connects the main 70 portion of the cylinder and the supplemental hollow extension. At the lower end of the main portion 2 of the cylinder is the crank case 5 which is air tight and which contains a body of oil, not shown, in the usual manner. 6 indicates a hollow piston consisting of the main portion 7, a hollow plunger 8 and a suitable connecting portion 9, in the present instance of tapered formation, between the portions 7 and 8. The piston 6 is 80 connected to the crank shaft 10 by means of the crank 11 and connecting rod 12 in the usual manner. 13 is the fuel inlet which extends through the cylinder to the piston and which is normally cut off by the latter. 14 85 is the exhaust port leading from the annular chamber 15 which communicates with the main portion of the cylinder by means of the ports 16 at the proper point in the cycle of the machine. 17 indicate ports in the 90 hollow plunger establishing communication between the said hollow plunger and the cylinder. Adjacent to the ports 17 is the conical-shaped fire-screen 18 which prevents explosion within the piston. 19 is the ignition means shown here as a spark plug of 95 conventional type.

It will be noted that the cylinder and the piston together form a combustion chamber having an end portion of relatively small 100 capacity which gradually widens in one direction, and that the hollow piston, the cylinder and the crank case form a crank case compression chamber.

Within the hollow piston there is a longitudinally extending conduit 20 which communicates at all times with the hollow piston and which has an inlet 21 opening transversely into the fuel inlet 13 on the compression stroke of the piston. It will fur- 110

ther be noted that the walls of the said conduit shields the incoming fuel from the splash in the crank case.

At the end of the compression stroke the 5 ports occupy the position shown in Fig. 1 and fuel will now flow through the inlet 13 into the conduit 20 and thence into the interior of the piston and the compression chamber formed by it and the other ele-

10 ments of the machine.

Substantially at the completion of the power stroke, as shown in Fig. 2, the ports 16 open up communication between the cylinder and the chamber 15, and the ports 17 15 permit the fuel to flow from the hollow piston into the narrowest point of the end portion of the combustion chamber.

What is claimed, is:

1. A two-cycle engine comprising: a cylinder, having a crank case, and a hollow piston, said elements forming a combustion chamber and a crank case compression chamber, said hollow piston communicating at all times with the crank case and having 20 ports at the upper end which at suitable intervals communicate directly with the combustion chamber and a conduit extending longitudinally of said piston and arranged to deliver fuel into the upper end of said 25 piston at other intervals.

2. A two-cycle engine comprising: a cylinder having a crank case and a hollow piston, said elements forming a combustion chamber having an exhaust port at one end 30 and a crank case compression chamber, said hollow piston communicating at all times with the crank case and having ports which open directly into said combustion chamber at the end remote from the exhaust port at 35 the end of the power stroke, a fuel inlet through the cylinder to the piston normally cut off by the latter, and a conduit within 40 said hollow piston normally open to the upper end of the piston adjacent said ports 45 and adapted to communicate with the inlet on the compression stroke of the piston.

3. An internal combustion engine comprising: a cylinder forming at one end a crank-case compression chamber and at the 50 other end a combustion chamber having an

extension, a hollow piston open to said compression chamber and having an extension operable in said cylinder extension, said piston extension being provided with ports which open directly into the combustion chamber at the end of the power stroke, and a conduit arranged to deliver fuel into said piston extension at the end of the compression stroke. 55

4. An internal combustion engine comprising: a cylinder forming at one end a crank-case compression chamber and at the other end a combustion chamber having an extension, a hollow piston open to said compression chamber and having an extension 60 operable in said cylinder extension, said piston extension being provided with ports which open directly into the combustion chamber at the end of the power stroke, a fuel inlet in the cylinder, and a conduit in 65 said piston adapted to convey fuel from said inlet into said piston extension at the end of the compression stroke. 70

5. An internal combustion engine comprising: a cylinder forming at one end a 75 crank-case compression chamber and at the other end a combustion chamber having an extension, a hollow piston open to said compression chamber and having an extension operable in said cylinder extension, said piston extension being provided with ports which open directly into the combustion chamber, and a conduit in said piston extending substantially the full length thereof and adapted to convey fuel into the piston extension, said fuel passing from the point of delivery in said piston extension through said hollow piston to said combustion chamber, and said hollow piston serving to directly convey fuel from said compression chamber through said ports into 80 said combustion chamber. 85

Signed at New York in the county of New York and State of New York this 11th day of March A. D. 1915.

CHARLES A. JUENGST.
